FLOODLIGHT

Eldon L. Anderson, Jr., Fletcher, N.C., assignor to
General Electric Company

Filed Nov. 18, 1971, Ser. No. 200,269

Term of patent 14 years

Int. Cl. D26—03

U.S. Cl. D48—20

Fig. 6.

Fig. 7.

Fig. 8.

FIG. 1 is a top plan view of a floodlight embodying my new design;

FIG. 2 is a front elevational view thereof;

FIG. 3 is a side elevational view thereof;

FIG. 4 is a rear elevational view thereof;

FIG. 5 is a bottom plan view thereof; and

FIGS. 6, 7 and 8 are perspective views thereof.

The support members indicated in broken lines are shown for illustrative purposes only.

I claim:

The ornamental design for a floodlight, substantially as shown and described.
